PRODUCTION OF PALMITIC ACID

Hans George Kirschenbauer, Allendale, N. J., assignor to Colgate-Palmolive Company, Jersey City, N. J., a corporation of Delaware

No Drawing. Application January 31, 1951,
Serial No. 208,835

11 Claims. (Cl. 260—409)

1

Palmitic acid is an excellent raw material for the manufacture of soap, particularly hard soaps. It is also employed as an intermediate in making compounds suitable for many other industrial uses. It is present in rather substantial quantities among the component acids of many vegetable and animal oils including other fatty acids of an unsaturated nature such as oleic and linoleic. Tall oil obtained as a by-product derived from the waste liquor of pine oil pulp is a rich source of palmitic acid but this type of oil contains not only palmitic acid but other miscellaneous acids in solution therewith. Processes have been used for treatment of oil such as tall oil to produce palmitic acid. One such process is known as the Varrentrapp reaction, which per se has been known to chemists since about 1841. This reaction involves heating the vegetable oil containing the fatty acid radicals (such as the oleic acid radical) which it is designed to convert to palmitic acid in the presence of excess caustic such as KOH or NaOH. The temperature of heating is preferably of the order of about 320° C. when substantially anhydrous conditions are employed, but may be appreciably lower, such as of the order of about 260° C., if carried out in an autoclave in the presence of a substantial quantity of water. The conversion of the oleic to palmitic acid is accompanied by the generation of hydrogen.

It has been found that if the fatty oil used as a starting material in a process of the above-mentioned nature contains glyceride esters of other unsaturated acids besides oleic, such as linoleic, linolenic and similar unsaturated acids, the attempted conversion to palmitic acid is very small because in such cases the more highly unsaturated acids are broken down to saturated acids of shorter chain length, such as myristic from linoleic and lauric from linolenic acid.

It is therefore an object of this invention to provide a process which substantially increases the yields of the relatively more desirable palmitic acid resulting from the treatment of vegetable oils in the aforesaid manner.

Generally speaking, the process comprises two steps. First, the vegetable oil starting material is selectively hydrogenated under conditions such that the relatively more highly unsaturated fatty acids such as linoleic and linolenic acids normally present therein are largely or substantially completely converted to oleic acid without at the same time substantially affecting the oleic acid content; and second, the product of the selective hydrogenation is subjected to

the Varrentrapp reaction to convert the oleic acid component to the desired palmitic acid. The polyunsaturated fatty acids such as linoleic and linolenic acids are hydrogenated during the selective hydrogenation step to an oleic acid that may be present as such or in one or more of its isomeric forms, while at the same time the oleic acid originally present in combination as glycerides in the starting material remains substantially unaffected. The selectively hydrogenated material, in which most of the acids that were more highly unsaturated than oleic have been converted to oleic acids, is then subjected to a heat treatment in the presence of excess alkali such as caustic potash or caustic soda, whereupon the resultant product consists essentially of a relatively high percentage of palmitic acid soap resulting from the Varrentrapp reaction, which is conjectured as involving the migration of the double bond of the oleic acid toward the 16:17 position with subsequent cracking of the fatty acid between C₁₆ and C₁₇ to give the desired C₁₆ saturated acid component as a major reaction product.

In order to indicate still more fully the nature of the present invention, the following examples of typical procedure are set forth with the understanding that this is by way of illustration only, and not by way of limiting the scope of the invention.

30

Example I

An example of the process, carried out under substantially anhydrous conditions, is as follows:

A cottonseed oil containing as component acids the following: 20% palmitic, 30% oleic, 45% linoleic and 5% miscellaneous acids including some linolenic acid, is subjected to selective hydrogenation in order to convert the linoleic and linolenic acids present into oleic acids. By selective hydrogenation, it is to be understood that the conditions of hydrogenation under otherwise conventional conditions are carefully controlled so as to terminate the hydrogenation when substantially all the polyunsaturated acids have been converted to the monounsaturated oleic acid. The selective hydrogenation may be carried out at atmospheric or slightly elevated pressures, using known nickel hydrogenation catalysts of the "selective" type such as are commercially available. The temperatures of hydrogenation are preferably of the order of 160°-180° C., although variations somewhat on either end of this range may be resorted to without sacrificing all the advantages thereof.

2

Following the selective hydrogenation step, the hydrogenation catalyst is removed and the material is then subjected to reaction with excess caustic alkali, such as caustic soda or caustic potash or mixtures thereof, at elevated temperatures such as of the order of 300°-400° C. although preferably temperatures near the lower end of this range, such as 320° C., are employed. This results in a high yield of an alkali metal soap of palmitic acid. Upon separating this soap from the crude reaction mixture, and acidifying the soap, a water-insoluble fatty acid mixture is obtained which contains about 90% palmitic acid.

Example II

An example of the process, carried out under hydrous conditions, is as follows:

A corn oil having an iodine value of 126.4, and in which the major acid components are 8% palmitic, 4% stearic, 45% oleic, 41% linoleic and 2% miscellaneous, is subjected to selective hydrogenation at 165° C., using a conventional selective-type nickel hydrogenation catalyst in a hydrogenating vessel of the shaking type at a pressure slightly above 10 atmospheres. When the iodine value of the corn oil is substantially lowered, namely, to a value corresponding to that for the substantially complete conversion of the polyunsaturated acid components to monounsaturated acid components (i. e., to an iodine value of 70.8), the selective hydrogenation is discontinued. The hydrogenation catalyst is removed by filtration and 100 parts of the selectively hydrogenated corn oil product is transferred to a reaction vessel provided with external heating means and equipped with agitating means. 50 parts of an aqueous potash lye containing approximately 20 parts of anhydrous KOH are then added to the contents of this vessel. The mixture is agitated and the temperature is gradually increased to 320° C., to eliminate the water from the reaction mixture. To the molten mixture there is now added with constant agitation 150 parts of powdered anhydrous KOH. Heating is continued for 2 hours after all of the caustic has been added. The reaction mixture is cooled and taken up in about 400 parts of water. The grained-out soap, consisting principally of potassium palmitate is recovered by skimming, leaving the bulk of the unreacted caustic as well as the major portion of the potassium acetate produced during the Varrentrapp reaction in the lower aqueous layer. The soap thus obtained may be used, as such, or if desired it may be readily converted to palmitic acid by acidification followed by distillation. The potassium palmitate reaction product is obtained in high yield.

Other vegetable and animal oils having a substantial content of polyunsaturated acids of 18 carbon atoms or more, such as palm, soy bean, perilla, peanut, avocado, olive, olive oil foots and red oil, are suitable as starting materials. Also, any higher fatty acid mixture of suitable composition may be employed including soap stocks and acidulated soap stocks, or any other suitable higher fatty acid mixtures obtained by known processes, so long as these contain the polyunsaturated acids as just mentioned. Additionally, any known technique for obtaining high selectivity during hydrogenation in converting linoleic or linolenic acid to oleic acids may be used. Additionally, any suitable alkali besides caustic potash may be used such as caustic soda or mixtures of the two. The combination of selective hydrogenation and the Varrentrapp re-

action results surprisingly in high yields of palmitic acid. The combination of the two steps thus provides industry with a process which is very efficient and which eliminates the disadvantages in the processes already known in the art. The major disadvantage of all prior art processes was that the final product was relatively low in palmitic acid and relatively high in the shorter chain degradation products of the original fatty oil material. The present process on the other hand gives high yields of palmitic and low yields of the less desired shorter chain degradation products.

While specific examples of preferred methods embodying the present invention have been set forth above, it will be apparent that many changes and modifications may be made in the methods of procedure without departing from the spirit of the invention. It will therefore be understood that the examples cited and the particular proportions and methods of operation set forth above are intended to be illustrative only, and are not intended to limit the scope of the invention.

What is claimed is:

1. In a process for the production of palmitic acid from a fatty material containing polyunsaturated soap-forming fatty acid components, the steps that comprise selectively hydrogenating the fatty material to hydrogenate the polyunsaturated fatty acid components to oleic acid components, heating the resulting product containing oleic acid components produced by the selective hydrogenation to an elevated temperature in the presence of excess alkali to convert said oleic acid material to palmitic acid material, and recovering a palmitic acid-containing reaction product from the reaction mixture.

2. In a process for the production of palmitic acid from a fatty oil material containing high molecular weight polyunsaturated soap-forming fatty acid components of which the fatty acid radicals are of 18 carbon atom chain length, the steps that comprise selectively hydrogenating the fatty oil material to hydrogenate the polyunsaturated fatty acid components to oleic acid components, heating the resulting selectively hydrogenated product containing oleic acid components produced by the selective hydrogenation to a temperature of about 260° to 400° C. in the presence of excess alkali to convert said oleic acid material to palmitic acid material, and recovering a palmitic acid-containing reaction product from the reaction mixture.

3. In a process for the production of palmitic acid from a fatty oil material containing oleic acid and more highly unsaturated soap-forming fatty acid components of the group consisting of linoleic and linolenic acids, the steps that comprise selectively hydrogenating the fatty oil material to hydrogenate the more highly unsaturated fatty acid components to oleic acid components without substantially further hydrogenating the latter, heating the resulting selectively hydrogenated product containing oleic acid components produced by the selective hydrogenation in admixture with the originally present oleic acid components to an elevated temperature in the presence of excess caustic alkali to convert said oleic acid material to palmitic acid material, and recovering a palmitic acid-containing reaction product from the reaction mixture.

4. In a process for the production of palmitic acid from a fatty oil material comprising glyceride esters of oleic, linoleic and linolenic acids,

the steps that comprise selectively hydrogenating the fatty oil material in the presence of a selective hydrogenation nickel catalyst to hydrogenate the glyceride esters of linoleic and linolenic acids to glyceride ester of oleic acid, heating the selectively hydrogenated product containing augmented oleic acid produced by the selective hydrogenation to a temperature of about 260° to 400° C. in the presence of excess alkali to convert said oleic acid material to palmitic acid material, and recovering a palmitic acid-containing reaction product from the reaction mixture.

5. A process for the production of palmitic acid that comprises selectively hydrogenating a vegetable oil containing fatty acids therein to hydrogenate only the more highly unsaturated fatty acids therein to an oleic acid, heating the selectively hydrogenated product in the presence of excess alkali to convert oleic acid to palmitic acid soap, and acidifying the resultant reaction product to produce palmitic acid.

6. A process for the production of palmitic acid that comprises selectively hydrogenating a fatty acid mixture containing an oleic acid together with acids more highly unsaturated than oleic acid to hydrogenate only said more highly unsaturated acids to an oleic acid, heating the selectively hydrogenated product in the presence of excess alkali to convert oleic acid to palmitic acid soap, and acidifying the resultant reaction product to produce palmitic acid.

7. A process for the production of palmitic acid that comprises selectively hydrogenating a cottonseed oil to hydrogenate the more highly unsaturated fatty acids therein to an oleic acid, heating the selectively hydrogenated product in the presence of excess alkali to convert said oleic acid material to palmitic acid soap, and acidifying the resultant reaction product to produce palmitic acid.

8. A process for the production of palmitic acid that comprises selectively hydrogenating a cottonseed oil to hydrogenate the more highly unsaturated fatty acids therein to an oleic acid,

heating the selective hydrogenated product to about 300° to 320° C. in the presence of excess caustic potash to convert said oleic acid material to potassium palmitate, and acidifying the resultant reaction product to produce palmitic acid.

9. A process for the production of palmitic acid that comprises selectively hydrogenating a vegetable oil containing an oleic acid together with acids more highly unsaturated than oleic acid to selectively hydrogenate only the more highly unsaturated acids to an oleic acid, heating the selectively hydrogenated product in the presence of excess alkali to convert said oleic acid material to palmitic acid soap, and acidifying the resultant reaction product to produce palmitic acid.

10. A process for the production of palmitic acid that comprises selectively hydrogenating a vegetable oil containing an oleic acid together with acids more highly unsaturated than oleic acid to selectively hydrogenate only the more highly unsaturated acids to an oleic acid, heating the selectively hydrogenated product in the presence of excess caustic potash to convert said oleic acid material to potassium palmitate, and acidifying the resultant reaction product to produce palmitic acid.

11. A process for the production of palmitic acid that comprises selectively hydrogenating a cottonseed oil containing an oleic acid together with acids more highly unsaturated than oleic acid, including linoleic and linolenic acids, to hydrogenate only the more highly unsaturated acids to an oleic acid, heating the selectively hydrogenated product in the presence of excess caustic potash to convert said oleic acid material to potassium palmitate, and acidifying the resultant reaction product to produce palmitic acid.
